UNITED STATES PATENT OFFICE.

THOMAS FERNELEY WILEY, OF RAWDON, NEAR LEEDS, ENGLAND.

APPARATUS FOR WATERPROOFING TEXTILE FABRICS.

SPECIFICATION forming part of Letters Patent No. 411,081, dated September 17, 1889.

Application filed September 24, 1888. Serial No. 286,211. (No model.)

To all whom it may concern:

Be it known that I, THOMAS FERNELEY WILEY, a subject of the Queen of England, and residing at Rawdon, near Leeds, England, 5 have invented certain Improvements in an Apparatus for Waterproofing Textile Fabrics or Rendering them Water-Repellent, of which the following is a specification.

This invention consists of an apparatus for 10 waterproofing textile fabrics, whereby a waterproofing or water-repelling substance, agent, or compound is applied to the fabric in a solid state without a solvent, and wherein the fabrics are afterward heated to complete 15 the waterproofing. I apply any waterproofing or water-repelling substance, agent, or compound in this manner which is capable of being formed to a convenient shape and having a melting-point below what would 20 damage the fabrics, of which the following substances are good examples: stearine, spermaceti, ozocerite, paraffine wax, and Japanese wax, or other similar substances. These substances may be either applied separately or 25 in combination.

In the accompanying drawings, Figure 1 represents a longitudinal section of an apparatus adapted to apply waterproofing or water-repelling substances in the form of solid 30 slabs to textile fabrics. Fig. 2 is a plan view of the same with one side of the said slab of waterproofing substance and the holder in which it is mounted broken away to show the parts beneath in full. In the above figures 35 the apparatus is represented in conjunction with a cylinder drying-machine, which machine is preferably used for the purpose of drawing the fabrics through the apparatus, as well as subsequently heating them; but it is 40 obvious that other means may be used for this purpose. Figs. 3 and 4 are respectively a plan view and an elevation on a reduced scale of the form of slab of waterproofing substance preferably used.

45 The reel A, holding the fabric B to be operated upon, is mounted in bearings C, formed at the end of the side frames D. At the opposite end of the machine a hollow india-rubber cylinder E, preferably without an arbor 50 and filled with water, is mounted upon a roller F and is supported laterally by rollers

G and H. A slab J, of waterproofing substance, is fixed in the holder K and its under edge rests upon said cylinder. The holder K is provided with projections L at each end, 55 fitting between the vertical guides M, formed at the top of the frames D, and it is so arranged that the weight of such holder presses the slab J toward the cylinder E, which pressure may be increased as required by placing 60 a weight or weights upon the tray N, fixed to the top of holder K.

The fabrics are passed through the above-described apparatus in the manner represented by the broken lines B, Fig. 1, and are 65 connected to a "wrapper" passed through the cylinder drying-machine O, which draws such fabrics from the reel A over and under adjustable tension-bars P, under the roller F, between it and the cylinder E, causing such 70 cylinder to revolve, and round such cylinder, under the slab J, over the roller Q, and between the drying-machine cylinders R. The friction of the fabrics upon the slab J as they pass beneath gradually wears such slab away 75 and it is uniformly deposited upon the fabrics, and when such fabrics pass between the cylinders R of the drying-machine their heat melts the waterproofing substance thus deposited, causing it to run and coat the fibers 80 or become absorbed by the fabric, thereby rendering them water-repellent.

The amount of waterproofing substance applied in this manner may be regulated by adjusting the pressure of the slab J upon the 85 fabrics, which is readily done by increasing or decreasing the weight upon the tray N. Feed-screws T are fitted through the top of the holder K to push the slab J out as it becomes reduced.

90 As the india-rubber cylinder E is hollow and filled with water, it is extremely pliable and elastic, and is consequently particularly adapted to uniformly press the fabrics against the under edge of the slab J, although such edge may be irregularly or unevenly worn. Such cylinder also tends to remove creases from the fabrics and otherwise keep them straight.

100 The slabs J are made longer than the width of the fabrics, in order to allow of any slight lateral deviation thereof, and as the ends of

such slabs are not exposed to the same amount of friction as the parts constantly in contact with the fabrics I preferably bevel the ends S of the slabs, so that they are more easily 5 worn away.

The bars P are capable of adjustment in the slots U for the purpose of regulating the tension of the fabrics.

I claim—

- 10 1. In an apparatus for waterproofing fabrics, the combination of a mass of solid waterproofing material, a hollow cylinder of flexible material adapted to contain water arranged adjacent to the mass of waterproofing 15 material, and guides for the fabric to direct it between the said flexible cylinder and the mass of waterproofing material, substantially as set forth.
- 20 2. In an apparatus for waterproofing fabrics, the combination of a slab of solid waterproofing material, a holder therefor in which it slides, a cylinder of flexible material adapted to contain water held opposite the edge of the said slab of material, and guides for the 25 fabric which direct it to partially encircle the

said cylinder to cause it to revolve, substantially as set forth.

3. In a machine for waterproofing fabrics, the combination of a mass of solid waterproofing material, a hollow cylinder of flexible material adapted to hold water, and the supporting-rollers F, G, and H, which hold the said hollow cylinder against the mass of waterproofing material, substantially as set forth. 30

35 4. In a machine for waterproofing fabrics, the combination, with the devices for feeding the fabric through the machine, of a slab of solid waterproofing material of greater length than the width of the fabric to be waterproofed, and having its ends beveled, and a holder for the slab of waterproofing material, substantially as and for the purpose set forth.

40 In testimony whereof I have hereunto set my hand in the presence of the two subscribing witnesses. 45

THOMAS FERNELEY WILEY.
